UNITED STATES PATENT OFFICE.

GERRARD M. REDDY, OF BOWIE, LOUISIANA.

TRACK-CLEANER FOR SAWMILL-CARRIAGES.

1,144,916.

Specification of Letters Patent. Patented June 29, 1915.

Application filed September 1, 1914. Serial No. 859,674.

To all whom it may concern:

Be it known that I, GERRARD M. REDDY, a citizen of the United States, residing at Bowie, in the parish of Lafourche and State of Louisiana, have invented certain new and useful Improvements in Track-Cleaners for Sawmill-Carriages, of which the following is a specification.

This invention relates to the subject of sawmill appliances, and more particularly to track cleaners and wheel guards for sawmill carriages.

To this end, the invention has in view a simple and practical form of track cleaner designed to be used in connection with the wheels of a sawmill carriage, and comprising means for not only guarding and protecting the wheel, but also subserving the function of a cleaner to automatically and effectually clear the track rails of obstructing foreign matter such as sawdust, bark, wood chips, and in fact any foreign material or obstructions which it would be objectionable to have present on the tracks of a sawmill carriage. It is well known in the lumber industry that the presence of sawdust, bark, or other obstructing material on the tracks of the sawmill carriage seriously interfere with the proper movement and operation of the latter, and it has therefore been the aim of sawmill operators to provide devices for keeping the tracks clear of such material, as well as to prevent undue wear of the wheel and the tracks by the use of such devices.

Accordingly, it is the purpose of the present invention to provide such a device that will not only effectually exercise its cleaning function, but at the same time do so with a minimum amount of wear on the wheel, the track, and on the device itself. Furthermore, in this connection, the invention contemplates a device having wear members which are readily renewable and replaceable at small expense, so that the device, as an attachment, is practically indestructible as compared with similar devices heretofore used.

With these and other objects in view, which will readily appear as the nature of the invention is better understood, the same consists in the novel construction, combination, and arrangement of parts hereinafter more fully described, illustrated, and claimed.

Though susceptible of structural modifi-

cation, a preferable embodiment of the invention is shown in the accompanying drawings, in which—

Figure 1 is a side elevation, partly broken away, of a track cleaner constructed in accordance with the present invention and shown in operative relation to the wheel and the track of a sawmill carriage. Fig. 2 is a top plan view of the complete device, the wheel appearing in section to illustrate its propelling engagement with the device for moving it back and forth over the track. Fig. 3 is an enlarged horizontal sectional view of one end of the device showing the mounting of the filler wear blocks in combination with an end guard cap. Fig. 4 is an inside elevation of one of the side casing plates. Fig. 5 is a perspective view showing one of the end caps and the associated pair of wear blocks in separated relation. Fig. 6 is an inside elevation of one of the end guard caps.

Like reference characters designate corresponding parts in the several figures of the drawings.

The device as an entirety may be designated as an open floating casing, inasmuch as it loosely and freely receives the wheel of the carriage therein and is propelled thereby over the track.

In the drawings, the numeral 1 designates a wheel of the sawmill carriage which travels upon one of the track rails 2, and the open casing of the device not only embraces 90 and receives the lower portion of the wheel below the axle, but also has a loosely interlocked connection with the wheel to insure the propulsion of the cleaner back and forth over the track rail with the least possible 95 friction, as will presently appear.

The casing of the cleaner includes in its organization the opposite duplicate side casing plates 3 arranged in spaced parallel relation and a sufficient distance apart to admit therebetween the carriage wheel. These plates are preferably made of malleable iron castings, and each of the same has formed upon the inner side thereof a semi-annular or semi-circular bearing shoulder 4 projecting inwardly from the inside face of the plate and having a radius corresponding to that of the inner rim shoulder 5 of the rim 6 of the carriage wheel. Accordingly, when the casing plates are assembled with the other parts of the cleaner, the carriage wheel is so disposed therein that the inner

shoulders 5 of the wheel rim have a bearing engagement against the inner shoulders 4 of the casing plates, with the result of providing a loose interlocking connection between the wheel and the cleaner casing so that the wheel will positively move the casing back and forth over the track without contact with the wear members to be presently referred to. Also, a desirable feature of this interlocking connection is the lifting tendency which the wheel exerts on the cleaner when moving the latter along and over the track. This is due to the fact that the shoulders 4 and 5 are concentric, and when the wheel is moving in one direction, as for instance in the direction indicated by the arrow in Fig. 1, the bearing pressure of the rim shoulder 5 comes against the then rear portions α of the shoulders 4. The wheel turning in the direction of the arrow shown in Fig. 1 therefore tends to lift the rear portion of the cleaner and thereby ease the friction thereof on the track rail. This is reversed to the other end of the cleaner when the sawmill carriage moves in the other direction.

The ends of the cleaner are entirely enclosed and protected by the end guard caps 7. Each of these guard caps is preferably made of soft wearing metal, such as brass, and is also preferably made of a single casting. The same is substantially of a V-shape in cross section, having the opposite flat fender walls 8 joined or united at the central apex 9 of the casting which lies at an inclination to the perpendicular. In fact the entire end cap casting is formed so as to set in an upright position at an inclination with the lower front corner thereof projecting forwardly, and thereby forming a clearer point 10 which travels directly over and upon the track rail. This point, together with the laterally inclined fender walls 8 serve to meet the track obstructions and deflect the same laterally away from the rail. By reason of being made of soft metal, the contact of the said end guard caps with the rails will not cause any wear on the latter. Referring further to the structural characteristics of the end caps 7, each of the latter is formed at the edges of the inclined walls 8 thereof with the outside joint flanges 11 which overlap the end edges of the side casing plates 3 and form a tight joint therewith which prevents the entrance of foreign matter into the ends of the casing. By reason of the end caps thus overlapping the end edges of the casing plates 3, the ends of the casing are entirely closed by the end caps, and in addition to this function each of the end caps operates as a holding and locking means for a pair of filler wear blocks 12, 12, associated therewith.

The wear blocks 12 are preferably wooden blocks, cut across the grain, and constitute

the main wearing elements or members of the device, and while rigidly and firmly locked within the ends of the casing are intended to be readily removable and replaceable, as they become worn. To secure the firm seating thereof, within the ends of the casing, and the rigid locking together of the coöperating parts, the said blocks, as indicated, are arranged in pairs at each end of the casing. The blocks of each pair are also arranged respectively upon opposite sides of an inside central holding web 13 formed integrally with each end cap and projecting inwardly and centrally from the apex thereof between the opposite walls 8. The holding web 13 snugly registers and interlocks within a shouldered facial keeper seat 14 formed in the inner face of the block 12 of each pair of blocks, and in addition to this feature each block is provided with a beveled front edge 15 registering with one of the fender walls 8, and in one front corner with a plurality of keeper notches 16 which receive and interlock with a plurality of correspondingly shaped locking lugs 17 projecting inwardly from a wall 8 of the end cap 7, said lugs also engaging at the inner side of the casing plate 3 and coöperating with the outside joint flange 11 to properly hold the end of the casing plate with in and to the guard cap. With the parts in this assembled relation a plurality of fastening bolts 17^a rigidly tie them together, such bolts passing through alined bolt openings in the casing plates 3, the wear blocks, and in the central holding web 13.

As a matter of additional protection to the device itself, each side casing plate has formed thereon exterior rounded fender projections 18. These fender projections are located adjacent the ends of the casing plate and are upwardly convergent with relation to the outside joint flanges 11 of the end caps, which latter flanges are also rounded to act as fenders. The effect of said joint flanges projecting beyond the outer faces of the side plates, and more particularly of the fender projections 18, is to throw off heavy obstructions so as to protect the heads and nuts of the bolts which are located in the interval between said flanges and said fender projections.

In the operation of the device, it will be understood that the pairs of filler wear blocks take the main wear of the device, while at the same time efficiently performing the function of keeping the track rails smooth and clear in order to insure an even movement for the sawmill carriage. Furthermore, an important consideration in connection with the use of these blocks and the soft-metal end caps is that these active elements of the cleaner will not wear the track rails nor the wheels, which is one of the greatest objections to sawmill carriage

cleaners heretofore used. It may also be noted at this point that the carriage wheel does not engage the wear blocks but maintains its engagement with the shoulders 4 of the casing, and is kept clear of the wear blocks by the inner upper portions thereof being formed with wheel-clearance bevels 5. As a matter of fact, it will be observed that substantially the entire cleaning surface 10 of the device is provided for by the wooden wear blocks, these being of a relatively extended area covering the track rail to such a degree and in such a manner as to effectually clear the same of foreign matter without subjecting it to any wear. A small 15 area of the brass end caps will engage the rails and incidentally perform a cleaning function also, but this engagement with the rails will not impose any undue friction or 20 wear thereon.

Other advantages will appear to those skilled in the art, and it will be understood that changes in the form, proportion, and minor details of construction may be resorted to without departing from the spirit or sacrificing any of the advantages of the 25 invention.

I claim:

1. A track cleaner comprising an open 30 wheel-receiving casing having removable end caps, and removable wear blocks clamped within said caps.

2. In a track cleaner, an open wheel-receiving casing including side casing plates 35 and removable end caps, and removable wear blocks clamped within said caps.

3. In a track cleaner, an open wheel-receiving casing including side casing plates and removable end caps connecting the ends 40 of said plates, and removable wear blocks clamped within said caps.

4. A track cleaner comprising side casing plates having interior wheel engaging means, removable end caps connecting the 45 ends of said plates, and removable wear blocks clamped within said caps.

5. A track cleaner including opposite side casing plates, V-shaped end caps removably fitted to the ends of said plates, and a pair 50 of wear blocks removably locked within each end cap.

6. A track cleaner including opposite side casing plates, V-shaped end caps removably fitted to the ends of said plates, a pair of wear blocks having an interlocking engagement with each end cap, and fastening bolts 55 engaging the end caps, the side plates, and the wear blocks.

7. A track cleaner including opposite side plates, removable end caps connecting the 60 ends of said plates and each provided with an inside central holding web, a pair of wear blocks fitting within each end cap and arranged respectively upon opposite sides of the holding web thereof, and fastening bolts 65 engaging the side plates, the wear blocks, and the holding webs of the end caps.

8. A track cleaner including opposite side plates, removable end caps connecting the 70 ends of said plates and each provided with an inside central holding web, the walls of said end caps being further provided with inwardly projecting locking lugs, a pair of wear blocks fitting within each cap and arranged respectively upon opposite sides of 75 the holding web, each wear block having upon its inner side a facial keeper seat receiving said web and also provided with keeper notches interlocking with locking lugs of the end cap, and fastening bolts 80 engaging the side plates, the wear blocks, and the holding webs of the end caps.

9. A track cleaner including opposite side plates, V-shaped end caps having outside joint flanges engaging over the end edges of 85 said plates, and wear members within the end caps.

10. A track cleaner including opposite side casing plates provided with exterior fender projections adjacent the ends thereof, wear 90 members held between the casing plates, and fastening bolts engaging the casing plates and wear members and having their heads and nuts disposed adjacent said fender projections. 95

In testimony whereof I hereunto affix my signature in the presence of two witnesses.
